UNITED STATES PATENT OFFICE.

GOTTLIEB WUELTER, OF COLUMBUS, OHIO.

MACHINE FOR HARDENING STEEL.

1,113,723.

Specification of Letters Patent.

Patented Nov. 24, 1914.

Application filed October 9, 1913. Serial No. 794,317.

To all whom it may concern:

Be it known that I, GOTTLIEB WUELTER, a citizen of the United States of America, residing at Columbus, in the county of Franklin and State of Ohio, have invented certain new and useful Improvements in Machines for Hardening Steel, of which the following is a specification, reference being had therein to the accompanying drawing.

10 This invention relates to a machine for hardening steel and other metals, and the primary object of my invention is to provide positive and reliable means, in a manner as hereinafter set forth, for subjecting a piece of heated metal to a hardening solution or liquid under pressure, whereby a piece of metal will be evenly and uniformly tempered.

Another object of this invention is to provide a machine for hardening metal where-in liquid under pressure is utilized for hardening a piece of metal, and by controlling the pressure of the liquid pieces of metal can be hardened alike.

25 A further object of this invention is to eliminate the cracking and uneven hardening of a piece of metal by simultaneously subjecting all exposed surfaces thereof to the action of a liquid under pressure.

30 A still further object of this invention is to provide a machine for hardening steel and other metals that consists of comparatively few parts that are inexpensive to manufacture, easy to assemble, durable, and highly efficient, for the purposes for which they are intended.

With the above and other objects in view the invention resides in the novel construction, combination and arrangement of parts, 40 to be hereinafter specifically described and claimed.

Reference will now be had to the drawing, wherein:

45 Figure 1 is a vertical sectional view of the machine, Fig. 2 is a horizontal sectional view of a portion of the same taken on the line II--II of Fig. 1, Fig. 3 is a similar view taken on the line III--III of Fig. 1, Fig. 4 is a front elevation of the tempering cylinder, and Fig. 5 is a vertical sectional view of the same.

A machine in accordance with this invention comprises a cylindrical tank 1 adapted to contain water, oil or a hardening solution which is placed within the tank through the medium of a funnel connection

2 carried by the top of said tank, said funnel connection having a shut off valve 3. One side of the tank 1 has a gage glass 4 and a drain cock 5, said gage glass showing the height of the contents of the tank and said drain cock permitting of the tank being drained and flushed.

Connected to the top of the tank is an air supply pipe 6 having a conventional form of shut-off valve 7. The top of the tank is provided with an exhaust valve 8 and with a pressure gage 9, said gage determining the amount of air pressure upon the liquid within the tank and said exhaust valve permitting of the pressure being reduced when excessive of what is desired.

The top of the tank has a goose-neck 10 provided with a down-pipe 11 that extends in proximity to the bottom of the tank 1. The outer end of the goose-neck has a shut-off valve 12 of the ordinary and well known type and said valve is connected to a tempering cylinder 13, secured, as at 14 to the side of the tank 1. The bottom of the cylinder is open and the front side thereof is cut away, as at 15 whereby the pieces of metal to be hardened can be easily placed in the cylinder.

Diametrically opposed inner walls of the cylinder 13 have vertical guide ribs 16 that extend into notches 17 in a movable head 18 arranged within the cylinder. The head 18 is slightly less in diameter than the cylinder and said head is perforated or apertured, as at 19. The bottom side of the head 18 is pivotally connected, as at 20 to toggles 21 and said toggles are supported by a transverse shaft 22 journaled in the lower end of the cylinder, said shaft having one end 95 thereof provided with a crank or lever 23 whereby the toggles can be moved to raise and lower the head 18.

Connected to the inner wall of the cylinder 13, adjacent to the lower end thereof is an adjustable stop 24 that can be shifted to limit the downward movement of the head 18.

A receptacle 25 is located beneath the cylinder 13 to collect such hardening liquid as passes through said cylinder.

In Figs. 4 and 5 of the drawing there are illustrated modified forms of toggles and operating levers.

A piece of metal is illustrated upon the head 18 in Fig. 1 of the drawing, and with a pressure of air upon the top of the harden-

ing liquid within the tank 1, the hardening liquid is forced upwardly through the pipe 11 into the top of the cylinder 13, where it encounters under pressure, the surfaces of 5 the piece of metal upon the head 18. The space between the head 18 and the walls of the cylinder and the apertures in said head allow a sufficient quantity of hardening liquid to pass through the cylinder to cool 10 the same.

My machine has been especially designed for hardening tool steel to a desired degree of hardness without cracking and to reduce shrinkage to a minimum of tools, such as 15 expensive dies, punches, forming tools, cutters, gages, templets, etc. With improved furnaces it is possible to heat any particularly shaped piece of tool steel slowly and uniformly, but to cool or dip it uniformly, 20 insuring an even and uniform hardness all over thereby preventing an uneven strain, which is the cause of cracking, it is necessary to place the piece of steel in an inclosed casting or cylinder, and for this reason I have 25 devised my machine, which embodies a cylinder in which a piece of steel can be subjected to a uniform and continuous flow of liquid, under regulated pressure, consequently the liquid will be forced in to the crevices and 30 against all the surfaces of the steel until completely cooled and hardened. Drinking or well water can be used to give absolute hardness, but the chances are large for a 35 piece of steel being cracked. Soft or rain water or oils will prevent cracking but do not give the hardness such as desired for all metal cutting edges, on account of being almost non-adhesive to a heated piece of metal or tool steel. But by forcing the same, in 40 the manner disclosed by my machine, a piece of steel can be uniformly hardened without

the hardening liquid vaporizing and with more uniform results than obtained by dipping hardened metal in a trough or receptacle.

From the foregoing it will be observed that with my improved machine one piece of metal can be hardened exactly like another piece, this being possible on account of maintaining the same amount of pressure and 50 flow of the hardening solution, consequently losses are avoided and a higher grade of product obtained.

While in the drawing there are illustrated the preferred embodiments of the invention, 55 it is to be understood that the structural elements are susceptible to such variations and modifications as fall within the scope of the appended claim.

What I claim is:—
A machine for hardening metal comprising 60 a tank adapted to contain a hardening liquid, connections for supplying and controlling an air pressure within said tank upon the contents thereof, a cylinder carried 65 by said tank and having connections therewith to receive the hardening liquid from said tank, a manually operated head movable in said cylinder and adapted to support a piece of metal whereby the same is subjected to the hardening liquid under pressure, means within said cylinder for limiting 70 the movement of said head, and means below said cylinder for collecting the liquid discharged therefrom.

In testimony whereof I affix my signature in the presence of two witnesses.

GOTTLIEB WUELTER.
